[57] CLAIM

The ornamental design for a self-contained rowing unit,
as shown and described.

DESCRIPTION

FIG. 1 is a perspective view of a self-contained rowing unit showing my new design;

FIG. 2 is a top plan view thereof;

FIG. 3 is a side elevation view thereof, the opposite side
being a mirror image of that shown;

FIG. 4 is an end elevation view thereof;

FIG. 5 is a top plan view of a self-contained rowing unit showing a second embodiment of my new design;

FIG. 6 is a side elevation view of FIG. 5, the opposite
side being a mirror image of that shown;

FIG. 7 is an end elevation view of FIG. 5;

FIG. 8 is a perspective view of FIG. 5.

The broken lines shown in FIG. 1 and FIG. 2 are for
illustrative purposes only.

FIG. I

FIG. 2
